UNITED STATES PATENT OFFICE.

JULIUS HANSEN AND PETER OLSEN, OF LADD, ILLINOIS.

COMBINATION-PADLOCK.

1,056,667.

Specification of Letters Patent. Patented Mar. 18, 1913.

Application filed December 11, 1911. Serial No. 665,058.

To all whom it may concern:

Be it known that we, JULIUS HANSEN, a subject of the Kingdom of Denmark, and PETER OLSEN, a citizen of the United States, residing at Ladd, in the county of Bureau and State of Illinois, have invented certain new and useful Improvements in Combination-Padlocks, of which the following is a specification.

10 This invention relates to locks and primarily to that class known as permutation padlocks.

The invention resides in the peculiar form of bolt operating member which coöperates 15 with a locking member, the latter being so constructed that when moved to an inoperative position, the bolt operating member may be moved to withdraw the bolt from engagement with the shackle or other member.

20 With the above and other objects in view, this invention consists of the construction, combination, and arrangement of parts, all as hereinafter more fully described, claimed 25 and illustrated in the accompanying drawings, wherein,

Figure 1 is a rear elevation of the lock closed, with one section of the casing removed to more clearly disclose the construction of the several parts. Fig. 2 is a similar 30 view, the lock being open. Fig. 3 is a sectional view taken on the line 3—3 of Fig. 1. Fig. 4 is an elevation of one section of the casing. Fig. 5 is a perspective view of the 35 bolt operating member. Fig. 6 is a perspective view of the locking member and the permutation ring or collar carried thereby.

Throughout the following detail description and on the several figures of the drawings, similar parts are referred to by like 40 reference characters.

In carrying out the present invention, a casing 1 is provided which is preferably constructed of two sections, each of which 45 is provided with an annular recess 2 and also a larger recess 3, the purpose of which will be hereinafter disclosed. Each section is provided with a pair of ears 4 and 4', the ears 4 having pivoted therebetween one end 50 of the shackle 5, while the hook end of the shackle is adapted to be guided between said ears 4' into the opening 6 in the casing. A bolt 7 is slidably mounted in the recess 3 and is adapted to move in an arcuate path 55 into engagement with the hook end of the shackle 5 for locking the latter from move-

ment. The inner surface of the bolt 7 is provided with the teeth 8 which mesh with the teeth 9 carried by the bolt operating member 10 rotatably mounted within the 60 casing 1. This member 10 is mounted on the shaft 11 which latter is actuated by a thumb wheel 12.

Formed on the peripheral edge of the member 10 and remote from the teeth 9 are 65 a plurality of stops 13 which are properly spaced to receive therebetween the locking pins or members 14, the latter being provided with recesses 15 and rotatable by the thumb pieces or wheels 16. The walls of 70 the casing on each side of the recess 2 are provided with transverse grooves, as at 17, to form the bearings for the locking pins 14 so that the latter may be easily rotated to bring the recesses 15 into alinement with the 75 stops 13 to receive the latter on movement of the bolt operating member 10 or rotate the recesses out of alinement whereby any movement of said member 10 is prevented. Each locking pin 14 is provided with a 80 square shouldered portion 18 on which is detachably and adjustably mounted the permutation rings or collars 19. It will be obvious that the shouldered portion 18 abuts against the sides of the annular recess 2 and 85 prevents the pin from displacement from the casing of the lock. Said shouldered portion also performs another function, in that it locks the permutation collar 19 upon the pin when in its normal position in the 90 annular recess, as well as connects the pin and collar for rotation on the latter, by means of the wheels 16. By having these permutation members 19 adjustably mounted different combinations may be obtained 95 if it is so desired.

From the foregoing, it will be observed that when the pins 14 are rotated to bring the recesses 15 in alinement with the stops 13, the bolt operating member 10 may be 100 rotated to withdraw the bolt from engagement with the shackle 5. Upon reversing the movement of the member 10, the bolt is again engaged in the hook terminal of the shackle 5 after which the locking pins 14 105 are rotated, thereby locking said member 10 from movement. Of course, it is understood that it is not necessary that all the locking pins should be rotated to lock the member 10 from movement, as the moving of any one 110 locking pin whereby the recess 15 is moved from alinement with the stop 13 will be

sufficient to prevent movement of the member 10 and opening the lock.

Having thus fully described the invention, what is claimed as new is:—

5 In combination, a casing comprising sections, each section having an arcuate recess therein adapted to register with the recess of the other section when the sections are assembled, a shackle, a locking bolt adapted
10 to engage the shackle, means for operating the bolt, stops carried by the bolt operating means, a plurality of rotatable locking pins disposed radially in the casing and extending across the arcuate recesses in the sec-

tions, and a permutation collar carried by 15 each pin and in the recesses in the sections, the locking pins having their inner terminals provided with longitudinal grooves to receive the stops when the grooves are in alinement with the stops.

20 In testimony whereof we affix our signatures in presence of two witnesses.

JULIUS HANSEN.
PETER OLSEN.
